UNITED STATES PATENT OFFICE.

ANNA WALEROWICZ, OF WYANDOTTE, MICHIGAN.

FOUNTAIN PEN.

Application filed March 7, 1928. Serial No. 259,650.

This invention relates generally to writing devices, and has more particular reference to a novel ink choke means for a fountain pen.

The invention has for an object the provision of a device of the class mentioned, which is of simple durable construction, desirable and efficient in action, and which can be manufactured and sold at a reasonable cost.

The device consists of a fountain pen barrel attached at one end to a pencil barrel. The free end of the pen barrel is provided with a pen point which is connected with an ink tube within the pen barrel. A cap is provided to engage over the pencil end of the device to cover same when not in use, and a second cap having a projecting rubber, is provided to engage over the pen point end of the device to cover same when not in use. A clip for supporting the device to a user's clothing is attached to the pen barrel. The second mentioned cap when in place on the device holds certain pins in, which pins are connected with means for choking the ink tube of the pen to prevent ink leakage while the rubber of this cap is being used.

For further comprehension of the invention, and of the objects and advantages thereof, reference will be had to the following description and accompanying drawings, and to the appended claims in which the various novel features of the invention are more particularly set forth.

Referring to the accompanying drawing, forming a material part of this disclosure:

Fig. 1 is a side elevational view of a device constructed according to this invention.

Fig. 2 is a view similar to Fig. 1, but with the pen cap of the device removed therefrom.

Fig. 3 is a fragmentary side view of the pen barrel per se.

Fig. 4 is a horizontal sectional view, taken on the line 4—4 of Fig. 2.

Fig. 5 is a side view of the pen cap, a portion thereof being broken away.

Fig. 6 is a fragmentary vertical sectional view of the pen end of the device.

Fig. 7 is an enlarged fragmentary detail view thereof.

The reference numeral 12 indicates generally a fountain pen barrel connected at one end to a pencil barrel 13, as indicated at 14.

The free end of the pen barrel 12 has a tube 20 forced therein, and a pen point 21 and flow member 22 are forced in the tube 20.

55 An ink tube 23 is attached to the tube 20.

A cap 24 is engaged on the pencil barrel, so that the pencil end of the device may be covered when not in use. A cap 27 is formed with threads 28 engageable with threads 29 on the pen barrel 12, so that the pen end of the device may be covered when not in use. A rubber 30 is engaged in the tip of the cap 27. Air apertures 31 are formed in the cap 27 to aid in preventing ink from flowing to the pen point 21 when not in use.

60 Choke members 32 are pivotally connected to the inner side of the barrel 12, as at 33 and have grooves 34. Slide members 35 engage in the grooves, and rods 36 pivotally connect with the slide members. These rods extend 70 thru apertures in the barrel 12 and slightly project above the top of the barrel. Springs 37 act between the rods and the barrel to normally urge the rods into said extended positions. When the rods are in this extended 75 position, the choke members 32 are in inclined position indicated by dot-dash lines 38 in Fig. 6, so that the ink tube 23 is not pressed in or choked. The cap 27 has a flange 39 adapted to press the rods 36 in, when the cap 80 27 is engaged upon the barrel 12. This moves the members 32 into horizontal positions, and the tube 23 is pressed together, as a means for choking the flow of ink to the pen point so that the rubber 30 may be used 85 without ink leaking from the pen point. A clip 40 is attached to the barrel 12.

In operation, the device may be carried in a person's pocket with both end caps in place, use being made of clips 40 in the customary 90 fashion. In use, the cap 24 may be removed to expose the pencil. The rubber 30 may be used in conjunction with the pencil for erasing. In this condition of the device members 32 choke the tube 23 to aid in preventing ink from flowing off the pen point 21. Also the cap 24 may be engaged on the device, and 95 27 removed for use as a fountain pen.

While I have shown and described a preferred embodiment of my invention it is to be understood that I do not limit myself to the precise construction herein disclosed and the right is reserved to all changes and modifications coming within the scope of the invention as defined in the appended claims.

100 Having thus described my invention, what I claim as new and desire to secure by United States Letters Patent is:—

1. In a device of the class described, a fountain pen barrel, a pen point and a flow mem- 110

ber engaged in the barrel, an ink tube connected with the pen and flow member, choke members pivotally mounted to the barrel, and in horizontal positions being capable of choking the flow of ink in the said ink tube, spring actuated rods connected to normally urge the choke members to inclined positions, and a cap member engaged on the barrel, and holding the rods in restrained positions so that the choke members are horizontal.

2. In a device of the class described, a fountain pen barrel, a pen point and flow member engaged in the barrel, an ink tube connected with the pen and flow member, choke members pivotally mounted to the barrel, and in horizontal positions being capable of choking the flow of ink in the said ink tube, spring actuated rods connected to normally urge the choke members to inclined positions, the said rods projecting from the barrel and a cap member engaged on the barrel, and holding the extended portions of the rods in re-

strained positions so that the choke members are horizontal.

3. In a device of the class described, a fountain pen barrel, a pen point and flow member engaged therein, and a cap member engageable thereon, an ink tube within the barrel and connected with the pen and flow member, and a means for choking a flow of ink from the said tube to the pen and flow member, arranged for operation upon engagement of the cap upon the barrel.

4. In a device of the class described, a fountain pen barrel, a cap member engageable thereon, an ink tube within the barrel, and a means for forcing opposite portions of the tube together so as to choke a flow of ink therefrom, and arranged for operation upon engagement of the cap upon the barrel.

In testimony whereof I have affixed my signature.

ANNA WALEROWICZ.
